(57) CLAIM

The ornamental design for a table napkin dispenser, as shown and described.

DESCRIPTION

FIG. 1 is a perspective view of the table napkin dispenser, the table napkin dispenser including broken lines, which are used in the present drawing and throughout the drawings to represent environment and which form no part of the claimed invention;

FIG. 2 is a front view in elevation of the table napkin dispenser;

FIG. 3 is a side view in elevation of the table napkin dispenser;

FIG. 4 is a side view (side opposite the side illustrated in FIG. 3) in elevation of the table napkin dispenser;

FIG. 5 is a top plan view of the table napkin dispenser; and, FIG. 6 is a bottom plan view of the table napkin dispenser.
